UNITED STATES PATENT OFFICE

MILDRED E. McFARLAND, OF SAN FRANCISCO, CALIFORNIA, ASSIGNEE TO THE STATION
FURNITURE MANUFACTURING COMPANY, OF HAGERSTOWN, MARYLAND, A CORPO-RATION OF MARYLAND

DESIGN FOR A BOX FOR COSMETICS

Application filed April 11, 1933. Serial No. 47,759. Term of patent 3½ years.

To all whom it may concern:

Be it known that I, MILDRED E. McFAR-LAND, a citizen of the United States, and a resident of the city and county of San Francisco, State of California, have invented a new, original, and ornamental Design for a Box for Cosmetics, of which the following is a specification, reference being had to the accompanying drawing, forming part thereof.

Figure 1 is an isometric view showing the box closed; and

Figure 2 is a similar view showing the box open.

I claim:

The ornamental design for a box for cosmetics, as shown.

MILDRED E. McFARLAND.

CERTIFICATE OF CORRECTION.

Design No. 90,257.
